UNITED STATES PATENT OFFICE

161,236

RACK FOR PLAYING CARDS

Carl A. Bissman, Springfield, Mo.

Application November 23, 1949, Serial No. 6,229

Term of patent 3½ years

(Cl. D34—13)

To all whom it may concern:

Be it known that I, Carl A. Bissman, a citizen of the United States, residing at Springfield, in the county of Greene and State of Missouri, have invented a new, original, and ornamental Design for a Rack for Playing Cards, of which the following is a specification, reference being had to the accompanying drawing, forming part thereof.

Figure 1 is a perspective view of a rack for playing cards, showing my new design.

Figure 2 is a side elevational view thereof, and Figure 3 is an end elevational view of the same.

I claim:

The ornamental design for a rack for playing cards, as shown.

CARL A. BISSMAN.
